J. PARMLEY.
HAT BRIM STIFFENER.
APPLICATION FILED OCT. 12, 1920.

1,378,977.

Patented May 24, 1921.

WITNESS:
Mr. M. Bell.

INVENTOR:
John Parmley,
By
John Edward.
ATTORNEY

UNITED STATES PATENT OFFICE.

JOHN PARMLEY, OF PATERSON, NEW JERSEY.

HAT-BRIM STIFFENER.

1,378,977.

Specification of Letters Patent.

Patented May 24, 1921.

Application filed October 12, 1920. Serial No. 416,418.

To all whom it may concern:

Be it known that I, JOHN PARMLEY, a citizen of the United States, residing at Paterson, in the county of Passaic and State 5 of New Jersey, have invented certain new and useful Improvements in Hat-Brim Stiffeners, of which the following is a specification.

This invention relates to a stiffener for 10 more or less flexible brims of hats, as felt hats, so constructed as to perform its intended function efficiently and yet be practically inconspicuous. My invention contemplates a hat-brim stiffening device including a body 15 part adapted to be secured to and having a piercing portion adapted to penetrate the crown-including part of a hat and a brim-stiffening part proper rigidly projecting from the body part, the piercing portion by 20 penetrating the crown-including part of the hat being adapted to obtain substantial purchase or hold on the hat. My invention further contemplates a hat-brim stiffening device formed of a piece of attenuated stiff 25 material, as a piece of wire, the end portions of said piece being curved to conform with the contour of a hat crown and being adapted to be secured to the hat and the intermediate portion being a bend projecting 30 outwardly from and joining said end portions and forming the stiffening part proper of the device.

In the accompanying drawing,

Figure 1 shows a hat in perspective, partly 35 broken away, and provided with the improved hat stiffener;

Fig. 2 is a horizontal sectional view of what is shown in Fig. 1, taken just above the hat-brim and the band or ribbon *e* being 40 removed;

Fig. 3 is a view similar to Fig. 2 but showing a different form of the stiffener; and,

Fig. 4 is a sectional view on the line 4-4, Fig. 2.

The drawing shows a soft felt hat by way 45 of illustration, *a* being the crown of the hat, *b* its brim, in the present case having its edge *c* folded upwardly and back, *d* the sweat band stitched to the hat in the usual 50 way where the brim joins the crown, and *e* the exterior ornamental band or ribbon.

In that form of my invention shown in Figs. 1, 2 and 4 the brim stiffening device is composed of a piece of wire whose extremities, *f f*, which together form the body part 55 of the device, project in opposite directions

and are curved substantially to the contour of a hat-crown, the intermediate part of the wire being shaped to form an outwardly projecting bend *g* which is preferably flaring in form. The hat is provided with two holes *h h* in the crown, at the front thereof, through which the legs or extremities *f f* of the stiffening device project, the said legs lying between and being held between and 60 by the crown and the sweat band *d*. The bend or brim-stiffening part proper *g* rests upon the brim (and it may be bent so as in side elevation to conform therewith—see Fig. 4) and may be secured thereto by stitching *i*. 65

In that form of the invention which is shown in Fig. 3 a piece of wire is bent to form the legs *k k*, which compose the body part of the device, and the intermediate 70 bend or brim-stiffening part proper *l*, all substantially the same as in the form first described, excepting that the ends of the legs or extremities *k* are bent inwardly in the form of hooks *m*. In this form of the 75 device of the legs *k k* embrace the crown, and their hooks are inserted through holes provided for them in the crown, as shown, the bend *l* resting on the hat-brim the same as in the form first described and being 80 secured thereto by stitching *n*. If desired, the bend or hat-stiffening part proper of the device may be covered by a suitable piece 85 of fabric *p* which matches the brim (Fig. 1).

In the drawing I show the bend or brim-stiffening part proper arranged at the front 90 of the hat, because it is there that a hat is usually grasped.

Having thus fully described my invention, what I claim as new and desire to secure by Letters Patent is:— 95

1. A hat-brim stiffening device including a body part adapted to be secured to and having a piercing portion adapted to penetrate the crown portion of a hat and a brim-stiffening part proper rigidly projecting from the body part. 100

2. A hat-brim stiffening device including a body part adapted to be secured to the crown portion of a hat and a brim stiffening part proper rigidly projecting from the body part, said body part comprising a pair of piercing members curved to the contour of a hat crown and adapted to penetrate 105 said crown-including portion. 110

3. A hat-brim stiffening device formed of a piece of attenuated stiff material, the end

portions of said piece being curved to conform with the contour of a hat crown and being adapted to be secured to the hat and the intermediate portion being a bend projecting outwardly from and joining said end portions and forming the stiffening part proper of the device.

4. A hat-brim stiffening device formed of attenuated stiff material and including a

pair of legs curved to conform with the contour of a hat crown and brim-stiffening means projecting from said legs, the device being adapted to be secured to a hat with the legs substantially concentric with the crown of the hat and the stiffening means extending across the brim thereof.

In testimony whereof I affix my signature.
JOHN PARMLEY.
